UNITED STATES PATENT OFFICE.

BARTON P. JENKS, OF PROVIDENCE, RHODE ISLAND, ASSIGNOR TO GORHAM MANUFACTURING COMPANY, OF PROVIDENCE, RHODE ISLAND, A CORPORATION OF RHODE ISLAND.

DESIGN FOR A LIQUID-SERVER OR SIMILAR ARTICLE.

49,845.

Specification for Design.

Patented Nov. 7, 1916.

Application filed August 2, 1916. Serial No. 112,863. Term of patent 14 years.

To all whom it may concern:

Be it known that I, BARTON P. JENKS, a citizen of the United States, residing at Providence, in the county of Providence and State of Rhode Island, have invented a new, original, and ornamental Design for Liquid-Servers or Similar Articles, of which the following is a specification, reference being had to the accompanying drawings, forming part thereof.

Figure 1 is a side view of the liquid server, showing my design. Fig. 2 is a back view, and Fig. 3 is a front view.

I claim:

The ornamental design for a liquid server or similar article, as shown.

BARTON P. JENKS.

Witnesses:

ADA E. HAGERTY,
J. A. MILLER.
